US0D1016821S

(12) **United States Design Patent** (10) Patent No.: **US D1,016,821 S**
(45) Date of Patent: ** Mar. 5, 2024

(54) **STAND FOR SUPPORTING A COMPUTING DEVICE**

(71) Applicant: **Roost Industries Corp.**, Aurora, CO (US)

(72) Inventors: **James Dotson Olander**, Denver, CO (US); **Zachary Earl Conrad**, Denver, CO (US)

(73) Assignee: **Roost Industries Corp.**, Denver, CO (US)

(**) Term: **15 Years**

(21) Appl. No.: **29/797,937**

(22) Filed: **Jul. 4, 2021**

(51) LOC (14) Cl. **14-02**

(52) U.S. Cl.

USPC **D14/447**

(57) **CLAIM**

The ornamental design for a stand for supporting a computing device, as shown and described.

DESCRIPTION

FIG. 1 is a perspective view of a stand for supporting a computing device showing first embodiment of the new design.

FIG. 2 is a front perspective view thereof;

FIG. 3 is a rear perspective view thereof;

FIG. 4 is a front elevation view thereof;

FIG. 5 is a rear elevation view thereof;

FIG. 6 is a left elevation view thereof;

FIG. 7 is a right elevation view thereof;

FIG. 8 is a top plan view thereof;

FIG. 9 is a bottom plan view thereof;

FIG. 10 is a front perspective view of the stand shown in a collapsed position of use;

FIG. 11 is a rear perspective view of the stand shown in a collapsed position of use;

FIG. 12 is a front elevation view thereof;

FIG. 13 is a rear elevation view thereof;

FIG. 14 is a left elevation view thereof;

FIG. 15 is a right elevation view thereof;

FIG. 16 is a top plan view thereof;

FIG. 17 is a bottom plan view thereof;

FIG. 18 is a front perspective view of the stand shown in a collapsed position of use, wherein pull tabs are in an extended configuration;

FIG. 19 is a rear perspective view of the stand shown in a collapsed position of use, wherein the pull tabs are in an extended configuration.

FIG. 20 is a front perspective view of the stand for supporting a computing device showing a second embodiment of the new design.

FIG. 21 is a rear perspective view thereof;

FIG. 22 is a front elevation view thereof;

FIG. 23 is a rear elevation view thereof;

FIG. 24 is a left elevation view thereof;

FIG. 25 is a right elevation view thereof;

FIG. 26 is a top plan view thereof;

FIG. 27 is a bottom plan view thereof;

FIG. 28 is a front perspective view of the stand shown in a collapsed position of use;

FIG. 29 is a rear perspective view of the stand shown in a collapsed position of use;

FIG. 30 is a front elevation view thereof;

FIG. 31 is a rear elevation view thereof;

FIG. 32 is a left elevation view thereof;

FIG. 33 is a right elevation view thereof;

FIG. 34 is a top plan view thereof; and,

FIG. 35 is a bottom plan view thereof.

The broken lines shown in FIG. 1 are for the purpose of illustrating environment and form no part of the claimed design.
